PROCESS FOR TREATING NAPPED FABRICS
 George W. Lemieux, Swannanoa, N.C., assignor to
 Beacon Manufacturing Company, a corporation of
 Delaware
 No Drawing. Filed Sept. 21, 1964, Ser. No. 397,676
 3 Claims. (Cl. 8—115.6)

This invention relates to a process for treating napped fabrics and more especially to a process for treating blanket fabric with a unique resinous composition that establishes and maintains the desired resilience in the napped surface and also the desired softness.

Napped untreated blanket fabric may have a relatively high loft originally but this property will be diminished substantially through normal use of the blanket. Also, untreated blankets made of synthetic fibers will shed the napped fibers quite extensively when laundered.

Attempts to eliminate these disadvantages by treatment of the blanket fabric with the usual synthetic thermosetting resins alone are not satisfactory because these resins render the fabric relatively stiff or harsh and boardy.

It has also been found unsatisfactory to treat the blanket fabric with thermoplastic type resins alone because they render the blanket "mushy" and give it a lifeless clammy feel.

In accordance with the present invention a blanket having a durable high loft, a soft feel and a lively resilient characteristic is obtained for the first time. This heretofore unobtainable objective is made possible by treatment of the fabric with a resinous composition that contains a thermosetting, cellulose reactive component and a fiber coating thermoplastic component, along with other constituents, admixed in proper proportions. Treatment of the synthetic fiber fabrics with this type of composition also prevents the usual undesirable pilling and shedding of the synthetic fiber.

Treatment of the fabric with the above unique composition should be carried out in a manner to effect thorough impregnation and coating of the napped fibers. One requirement for this result is to have the untreated napped fibers opened up and in upstanding position and to maintain them in this position during the resin treatment and the finishing operations.

A suitable mechanical arrangement for opening up and maintaining the napped fibers in open upstanding position is described and claimed in George W. Lemieux application Serial No. 335,307, filed January 2, 1964, entitled Mechanisms and Method for the Production and Treatment of Napped Fabrics. While the chemical process of this invention is not limited to a particular mechanical arrangement, it has been found to work very satisfactorily with the apparatus disclosed in the above Lemieux patent application, and serves the chemical counterpart or complement thereof for producing the desired resilient, anti-pilling and anti-shedding blanket nap. In this preferred process, the blanket fabric is first napped on a napping drum, and the napped fabric fed over lead-in rolls covered with napping clothing to maintain the napped fibers in upright position, and then fed on an endless conveyor member, through a closed chemical treating chamber and finally through a heating chamber for drying the fabric and curing the resin impregnant and coating, as illustrated, described and claimed in the above Lemieux patent application.

The chemical treating process of the present invention takes place in the above mentioned closed chemical treating chamber and heating chamber. The present application being directed to a chemical process, independently of any specific apparatus used therefor, does not require illustration or detailed explanation of the equipment, but reference to the illustrations and description in the above

2

Lemieux application for details of one suitable form of apparatus may be made if desired.

For carrying out the chemical process of the present invention, a chemical composition comprising the following materials may be used. The parts of the individual ingredients forming the composition are given by weight of solids, unless otherwise indicated.

<i>Chemical composition</i>		Parts
10	Thermosetting resin, such as dimethylol ethylene urea, methylated methylol melamine, methylated dimethylol urea, dimethylol triazine	40
	Partially polymerized water soluble urea formaldehyde resin	5-15
15	Thermoplastic resin, such as vinyl ketone/styrene copolymers, butadiene/styrene copolymers	15-20
	Glycol, such as ethylene glycol, diethylene glycol, triethylene glycol, etc.	7-12
20	Formaldehyde acceptor, such as urea or dicyandiamide	0-5
	Buffering agent, such as triethanol amine, diethanolamine, or tris(hydroxy methyl) amino methane, to adjust the pH to 6.5-7.0	3-8
25	The procedure for mixing or compounding the above resinous formulation without catalyst is as follows:	
	The thermosetting resin and the glycol lubricant are mixed, and to this mixture is added the partially polymerized urea formaldehyde resin, water and urea. This mixture is stirred, and to it is added the thermoplastic copolymer. The pH of the resulting mixture is then adjusted to a pH of about 6.5 to 7 by adding the required amount of buffering agent. These mixing steps may all be carried out at normal or room temperature.	
30	35	Depending upon the specific properties desired in the treated blanket and the specific chemicals used, some of the components in the above resinous composition may be varied. For example, the partially polymerized urea formaldehyde resin may vary from approximately 5 to 15 parts; the thermoplastic copolymer may vary from approximately 15 to 20 parts; and the formaldehyde acceptor may vary from approximately 0 to 5 parts. The amount of water added depends upon the desired viscosity for shipping and ultimate handling of the liquid resinous composition. If necessary, a small amount, such as for example about 1% or less, of an anti-foam may be used to control foaming of the composition.
40	45	The above composition may be catalysed with normal resin catalysts, such as amine hydrochloride, magnesium chloride, maleic acid, etc., typical formulas for which are as follows:
		<i>Amine hydrochloride catalyst</i>
50	2-amino 2-methyl propanol-1	26
55	Muriatic acid, 20° Bé.	30
	Water	44
	Total	100
		<i>Magnesium chloride catalyst</i>
60	Magnesium chloride hexahydrate	64
	Water	36
	Total	100
65		<i>Maleic catalyst</i>
	Maleic anhydride	50
	Water	50
70	Total	100
	Adjust pH to 3.5-4.0 with ammonia.	

The selected resinous composition and catalyst are maintained separate during storage and shipment, and are mixed just prior to use of the composition for treatment of the napped blanket cloth in accordance with this invention.

In a typical operation carried out in accordance with this invention, a fifty gallon batch of the resinous composition and catalyst is made up by mixing one hundred and twenty pounds of the liquid resinous composition, in approximately two-thirds volume of water, and adding fifteen pounds of the liquid catalyst and then bringing the total volume to fifty gallons with water. This final mixture is applied in the form of a fine mist or fog onto both sides of a cellulosic fiber-containing napped blanket fabric, as it passes through the above mentioned chemical treating chamber, this chamber being enclosed to maintain an atmosphere of the chemical in uniform, constant contact with the fabric, as it passes through the enclosed chamber. The fog or mist of treating chemical in this chamber penetrates the napped surfaces of the fabric to effect a thorough impregnation thereof with the chemical and it also forms a coating of the chemical on the napped fibers.

The passage of the napped fabric through the chemical treating chamber above described, is continuous and preferably constant and in a typical example may be at the rate of approximately 30 yards of the fabric per minute.

Promptly following treatment of the fabric in the treating chamber as above described, the resulting wet, napped fabric is passed through a heating chamber, which is heated in a suitable manner, such as for example with a flow of hot air through the chamber, or electrical heating units properly disposed in the chamber adjacent the path of the moving fabric. The speed of the fabric through this heating chamber and the temperature thereof are adjusted so as to effect drying of the fabric and curing of the resin components in the above described treating composition. In a typical case, the temperature in the heating chamber is maintained at approximately 330° F., and the speed of the fabric is approximately 30 yards per minute. During this drying and curing step of the process, the conditions are such that the thermosetting resin component of the composition, e.g. the methylated dimethylol urea resin, and the partially polymerized urea formaldehyde resin, will crosslink with the cellulose of the treated fabric. These components impart to the treated napped fabric the above described desired resilience, which the untreated fabric does not possess. This is particularly true of the methylated dimethylol urea resin component, and the partially polymerized urea formaldehyde resin component gives the fabric the desired hand.

The thermoplastic component of the resinous composition, forms the important function of coating the fibers and effecting cohesion therebetween which enables the fibers to resist abrasion encountered during normal use of the blanket and to resist shedding of the nap during use and laundering of the blanket.

The napped fabric which may be processed in accordance with the present invention may be composed of any of the textile fibers or mixtures of fibers, and the base

fabric is usually a woven fabric although knitted or non-woven fabric may be used for the napping and chemical processing treatments. Typical examples of fibers which may be used in the fabric are cellulosic fibers, e.g. cotton and rayon; natural fibers, such as wool; blends of cellulosic fibers with synthetic fibers, such as nylon; the acrylics, such as Orlon, Acrlan and Zefran; and polyester fibers.

As above mentioned, it is important for the purposes of the present invention to use a resinous composition containing both the thermosetting resin component and the thermoplastic resin component which cofunction to give the desired properties in the final blanket. The properties of durable high nap, resilience, resistance to pilling and shedding and at the same time, the desired soft hand, cannot be obtained by use of either of these resin components without the other.

Various changes may be made in the above described chemicals, compositions, and procedures without departing from the scope of the invention, as defined in the appended claims.

I claim:

1. A chemically treated napped cellulosic fabric having a high loft, permanent resilience, softness of hand and resistance to abrasion and shedding of the nap during use of the fabric and laundering thereof, said fabric having a surface of resilient upstanding napped fibers which are impregnated and coated with a resinous composition consisting essentially of a thermosetting resinous component selected from the group consisting of dimethylol ethylene urea, methylated methylol melamine, methylated dimethylol urea, and dimethylol triazole and a thermoplastic resinous component selected from the group consisting of vinyl ketone/styrene copolymers and butadiene/styrene copolymers, said thermoplastic resinous component being present in an amount between approximately one-third and one-half of the amount of the thermosetting component, by weight, said resinous composition being cured and being present in sufficient amounts to form an impregnant and a coating of the fibers throughout the napped surface of said fabric.

2. A product as defined in claim 1 wherein the napped fabric is a blanket.

3. A product as defined in claim 2 wherein the thermosetting resinous component is cross-linked with the cellulosic components of the blanket.
